UNITED STATES PATENT OFFICE

1,982,557

CONTAINER

Edgar Watson, Towson, Md., assignor, by mesne assignments, to The Nelson Corporation, Baltimore, Md., a corporation of Maryland

Application January 19, 1932, Serial No. 587,546
Renewed March 27, 1934

4 Claims. (Cl. 229—31)

This invention relates to improvements in containers, and more particularly concerns a container which may be formed from an original square blank by the provision of diagonal cutting 5 and score lines thereon.

One of the features of the present invention is the provision of a container having closed vertical edges, and having overlapping pairs of cover flaps, whereby the container may be closed and 10 sealed by a standard closing machine.

Another feature of the present invention is the construction of such a container from a blank, with a minimum of waste.

Another feature of the present invention is the 15 construction of such a container from such a blank, in which the lower pair of cover flaps are supported, even with a filling of loose or bulk material, during the preliminary closing operations.

20 With these and other objects in view, an illustrative form of blank and the container formed therefrom are shown on the accompanying drawings, in which:—

Figure 1 is a plan view of a blank.

25 Figure 2 is a perspective view showing the manner of folding the bottom, sides, and corner flaps during assembly.

Figure 3 is a view of the completed and closed container.

30 Figure 4 is a perspective view, on a larger scale than Figure 2, showing the association of the corner flaps with the vertical walls.

Figure 5 is a transverse sectional view, showing the association of the cover flaps with the vertical wall flaps.

35 Figure 6 is a transverse sectional view, on an enlarged scale, through the top of the closed container.

Figure 7 is a plan view of a modified form of 40 blank.

Figure 8 is a view corresponding to Figure 4, showing the folding of modified blank.

Figure 9 is a view corresponding to Figure 5, showing the association of the cover flaps, vertical wall flaps, and gussets.

45 In these drawings, Figure 1 shows that an originally square blank has formed thereon a plurality of scoring lines, comprising two sets at mutual right angles. These sets are each at 45° to the edges of the original blank. These score lines define a bottom B, sides S1 and S2, ends E1 and E2, end cover flaps CE1 and CE2, and side cover flaps CS1 and CS2, as well as the pairs of corner flaps EF11—SF11, EF12—SF12, 50 EF21—SF21, EF22—SF22, which latter are sep-

arated from one another by score lines 10 which are preferably formed at the opposite side of the blank from the score lines aforementioned, and which extend at 90° to the edges of the original blank. It will be noted that the score lines between the corner flap portions EF11—EF12, EF21—EF22, are slightly offset toward one another, relative to the same end wall, than the corresponding lines of the bottom B and of the end cover flaps CE1—CE2, for the purpose herein-after set forth.

Along the sides of the blank, substantially triangular notches having a right angle at the inner corner are provided by cutting away the material at the points 11, 12. The corners of the original 70 blank are cut away at 13, 14, so that the widths of the end and side cover flaps are each substantially one-half the corresponding dimension of the bottom B, so that the edges of these flaps will meet and abut in the closed container.

75 The blank so made is then assembled by folding the junctions of the bottom, side and end walls and the corner flaps as indicated in Figure 2, and continuing the folding operations until the side and end walls are at right angles to the bottom B. The pairs of corner flap walls EF11—SF11, etc., are thus folded flat against one another and extend inward above the bottom B. These paired flaps may then be folded against one of the vertical walls, for example the corner flaps 80 EF11—SF11 may be folded against the side wall S1 (Figure 4), and the cover flaps are then secured in any suitable manner as for example by the staples 15.

85 This completes a container having cover flaps attached to its four upper edges, and this container may now be loaded with any desired material in the usual manner. It will be particularly noted that the vertical edges between the side and end walls are closed from bottom to top, and 90 that there is no passage for material or even air below the top edge of the vertical walls, except through the material itself.

95 Owing to the slightly greater width of the bottom B and the end cover flaps CE1 and CE2, than the corresponding width of the end walls E1, E2, the corner flaps EF11—SF11, etc. will thus lie inside of the side walls, to provide ledges 16 adjacent each side wall upon which the corresponding cover flaps CE1, CE2 may rest, and thus 100 be prevented against downward movement into the container during closing. Since the cover flaps are all free to open and close during loading, it is obvious that the ordinary closing machine 105 may be employed for bringing the end cover flaps 110

CE1, CE2, into position, applying thereto cement as usual, and then folding the side cover flaps CS1, CS2, down onto the same, and for holding the several flaps in position until the cement has hardened.

In particular it will be noted that the container is formed of a single piece, comprising an original square blank which has been cut with notches and provided with score lines for determining the folding. This blank can be folded and stitched together by staples 15 in a normal stitching machine, and the container thus formed may be loaded and closed in normal loading and closing apparatus. The container has closed bottom edges and vertical edges, and is hence adapted for the packing of bulk material, and further since the cover flaps are sealed to one another, the container is assured against pilfering without destruction of parts or such damaging that the fact of a non-intact package is immediately apparent upon simple inspection.

While the several vertical walls have been referred to as side and end walls, it will be understood that these terms are interchangeable, and that a container of any desired dimension in width, length and height may be constructed, except that in the preferred form the horizontal dimension of the cover flaps which are first to be folded into position are slightly greater than the corresponding dimension of the vertical walls located beneath them. Further, the parts have been described with respect to a container, and referring to the portion B as the bottom, although it is obvious that the container may be turned through various angles and into other positions during assembly, loading, closing, and shipment.

The blank shown in Figure 1 may be constructed of a sheet of corrugated material in which the lines of corrugation extend parallel to two edges of the original sheet. In such event, the lines of corrugation extend at 45 degrees to the scoring lines which define the bottom, side and end walls, and side and end cover flaps, so that in the finished container the fold at no one of these lines is weakened by extending parallel to a line of corrugation: and the same diagonal relationship of scoring lines and lines of corrugation prevails at the junction at the pairs of corner flaps with their respective side and end walls.

In closing the container, it has been set forth above that the side and cover flaps are folded down into two parallel planes which overlap, and thus the cover flaps may be closed and secured together by a standard closing machine having cement rolls, this cement being applied for example between the dotted lines X—X in Figure 3. The central butt joint of the cover flaps CS1, CS2 may be closed if desired by application of the tape T shown in dotted lines in Figure 3. The free arrangement of the cover flaps, with respect to one another, lends itself to closing in the standard closing machine, especially in the preferred form where the inner plane is formed of cover flaps CE1, CE2 which are prevented from downward movement into the container by their support by the pairs of corner flaps SF11—EF11 as shown in Figure 5.

The modified form of blank shown in Figure 7 differs from that of Figure 1 in that the notches 11 are not cut out, but in lieu thereof scoring lines 20 are provided extending at a right angle to the adjacent edge of the original blank, while the scoring lines for the end walls E1, E2, are extended. In folding this blank, the corner flaps EF11, SF11, etc., may be folded inward as be-

fore, and thus the gusset pieces G11—H11 at either side of each scoring line 20 constitutes a substantially vertical flap when the box is assembled as by the staples 15 (Figure 8), so that the box may be loaded with bulk material, and then placed on a shaking or vibrating machine to cause the material to settle down into the body of the container. These gusset members thus serve to prevent spilling at the corner of the container. It will be understood that the flaps CS1, CS2, usually extend vertically and thus closely parallel the gusset members during the filling and shaking operations.

When the shaking operation has been completed, the container may be passed through the usual closing machine, where the score line 20 at each corner serves to facilitate the bending of the gussets until the gusset members G11—H11 lie parallel to one another, and are usually supported upon the top of the material, in the position shown in Figure 9. During this operation the end flaps CE1, CE2 have been folded down to partly close the container, and the closing is then completed in the machine by applying the usual cement, and then folding down the side cover flaps CS1, CS2, in the usual way.

It will be noted that in each instance the vertical corners of the box are selvedge, i. e. they do not expose raw edges of material, and further that the upper edges are likewise smooth where they fold down onto the material within the container.

Obviously, the illustrated forms are not the only ones which may be employed, and the corner flaps may be folded in other ways than those indicated, while still preserving the advantages of the selvedge edges. In the illustrated form, the exterior of the box is free at its two ends and two sides for advertising matter, which may be placed on the blank before it is folded: although obviously in other forms the interior of the container may be left free for the accommodation of goods of particular shapes.

It will be noted that the original blank may be of corrugated material, with the corrugations extending parallel to two opposed edges of the blank, and then the lines of corrugations will extend diagonally across the score lines separating the bottom, side, end, etc. walls, so that in the finished container the edges are substantially of the same strength, and the corrugations then may appear as indicated by the wavy lines showing at the edges of the blank in Figure 2.

Other changes may be made without departing from the scope of the appended claims.

Having thus described my invention, what I claim as new and desire to secure by Letters Patent, is:—

1. A container formed from an originally square blank and comprising integral bottom, vertical side and end walls, side and end cover flaps, and pairs of corner flaps integrally joined to adjacent side and end walls, said corner flaps in each pair being joined along a folding line, each pair of corner flaps being located against and secured to the inside of a side wall of the container whereby to form a container body which is entirely closed along its bottom and vertical edges, all said pairs being parallel and having top edges at the level of the joint between the end walls and the end cover flaps whereby the pairs of corner flaps provide supports for said end cover flaps in a single plane, said side cover flaps in the closed container overlying and being secured to said end cover flaps and closing the container.

2. A container formed from an originally square blank and comprising integral bottom, vertical side and end walls, said end walls having a lesser side-to-side dimension than the distance between the side walls, side and end cover flaps, and pairs of corner flaps integrally joined to adjacent side and end walls, said corner flaps in each pair being joined along a folding line, each pair of corner flaps being located against and secured to the inside of a side wall of the container whereby to form a container body which is entirely closed along its bottom and vertical edges, all said pairs being parallel and having top edges at the level of the joint between the end walls and the end cover flaps whereby the pairs of corner flaps provide supports for said end cover flaps in a single plane, said side cover flaps in the closed container overlying and being secured to said end cover flaps and closing the container, said end cover flaps having a greater side-to-side dimension, than said end walls whereby to rest on top of said pairs of corner flaps.
3. A container formed from an originally square blank and comprising integral bottom, vertical side and end walls, side and end cover flaps, and pairs of corner flaps integrally joined to adjacent side and end walls, said corner flaps in each pair being joined along a folding line, each pair of corner flaps being located against and secured to the inside of a side wall of the container whereby to form a container body which is entirely closed along its bottom and vertical edges, all said pairs being parallel and having top edges at the level of the joint between the end walls and the end cover flaps whereby the pairs of corner flaps provide supports for said end cover flaps in a single plane, and gusset members in integrally joined pairs, each pair being integrally joined to said end cover flaps and said corner flaps and providing when said cover flaps are open extensions of said vertical walls at the vertical edges of the container body and in the closed container underlying and supporting the end cover flaps, said side cover flaps in the closed container overlying and being secured to said end cover flaps and closing the container.
